D20319

UNITED STATES PATENT OFFICE.

HENRY CLAY BASCOM, OF LANSINGBURG, AND FRANCIS RITCHIE, OF TROY,
NEW YORK.

DESIGN FOR A COOKING-STOVE.

SPECIFICATION forming part of Design No. 20,319, dated November 18, 1890.

Application filed September 29, 1890. Serial No. 366,562. Term of patent 7 years.

To all whom it may concern:

Be it known that we, HENRY CLAY BASCOM and FRANCIS RITCHIE, citizens of the United States, residing, the said BASCOM at the village of Lansingburg, county of Rensselaer, and State of New York, and the said RITCHIE at the city of Troy, in said State and county, have invented and produced a new and original Design for Cook-Stoves, of which the following is a specification, reference being being had to the accompanying drawing, forming a part thereof, and consisting of a single figure, affording a view in perspective of our newly-designed stove.

15 The characteristic features of our design are oblique ribs inclosed by foliated scrolls, the geometrically-figured open-work, the foliated vines having scroll terminals inclosing a central shell ornament, the loops inclosing 20 representation of eggs, and the relative arrangement and superficial contour of parts provided with openings, all as hereinafter described and pointed out.

The legs A of the stove are provided at 25 their upper ends with a plain horizontal border-band A', a front ornament A², comprising a series of oblique ribs inclosed by foliated scrolls and side ornaments A³, consisting of a foliated scroll, and at their lower ends with a 30 cluster of berries A⁴, inclosed by foliated rib terminals.

The base B, top B', hearth-shelf B², and oven-shelf B³ each have upon their vertical sides or edges convexed surfaces severally 35 decorated by a horizontal row of conventionalized shell ornaments B⁴, a plain lower horizontal border band or rib B⁵, and an upper plain beveled border-band B⁶.

The shelf B³ presents on its upper surface 40 geometrically-figured open-work and is connected with the upper surface of the base by the legs B⁷.

The oven-door C is provided with two similar ornaments C'—one on the upper and the 45 other on the lower portion of the front surface—consisting of foliated vine-like ribs having scroll terminals and inclosing a central shell ornament and an end figure composed of a group of four small scrolls, two of which 50 are foliated, inclosing a series of short parallel sigmoidal ribs within the group.

At the middle part of each end portion of the front surface of the door is an ornament C², consisting of divergent scrolls inclosing a series of short ribs.

55 The fire-place door D has on the front of its lower or ash-pit portion a rectangular figure formed by the four right-line ribs D', and centrally of such figure another figure composed of four loop-and-egg ornaments D²—one 60 near each corner of the rectangular figure—and curved ribs which connect such loop-and-egg ornaments and inclose a central foliated scroll D³. The loops are severally parts of the curved ribs and resemble in appearance the 65 tongue of a tongue-and-egg ornament.

On the front of the upper or combustion-chamber portion of door D are two mica openings D⁴, surrounded by a foliated border-rib, with a loop-and-egg ornament D⁵ at the 70 upper outside corners of the mica openings, and a foliated scroll ornament D⁶ at the lower outside corners of such openings. The mica openings are separated by a vertically-elongated ornament composed of a patera in the 75 middle part, a loop-and-egg ornament at the ends, and a conventionalized rib-inclosed shell intermediately of the patera and loop-and-egg ornaments.

The front door F is provided on the upper 80 portion with four vertically-elongated mica openings F', arranged in a horizontal row, on the lower portion with six vertically-elongated draft-openings F², arranged in a horizontal row, and intermediately of such rows 85 of openings with a horizontally-elongated poke-opening F³, the lower portion of the door having its general front surface convexed with rounded vertical edges, and the upper portion of the door having its general front 90 surface plane with rounded upper and vertical edges.

What we claim as new is—

1. In a design for a stove, the design for a 95 stove-leg herein shown and described, consisting on the upper end of a plain horizontal border-band, a front ornament comprising a series of oblique ribs inclosed by foliated scrolls, and side ornaments, each composed of a single foliated scroll and on the lower end 100 of a cluster of berries inclosed by foliated rib terminals.

OVER

2. In a design for a stove, the design for an oven-shelf herein shown and described, consisting of geometrically-figured open-work on the top surface, a row of shell ornaments on 5 the convexed edges of the shelf, and leg-connections between the front edge of the shelf and the upper surface of the base.
3. In a design for a stove, the ornamental design on an oven-door herein shown and described, consisting of two similar ornaments, one on the upper and the other on the lower front, consisting of foliated vines having scroll terminals and inclosing a central shell ornament, and an end figure composed of a 15 group of four small scrolls, two of which are foliated, inclosing a series of short parallel sigmoidal ribs.
4. In a design for a stove, the ornamental design on the ash-pit section of a side fire-place door herein shown and described, consisting of a rib ornament on the front surface of the door, comprising a rectangular figure inclosing a central figure composed of four loop-and-egg ornaments, one near each corner 20 of the rectangular figure, and curved ribs which connect such loop-and-egg ornaments and inclose a central foliated scroll.
5. In a design for a stove, the ornamental design on the combustion-chamber section of 25 a side fire-place door herein shown and described, consisting of a foliated border-rib

around two mica openings, a loop-and-egg ornament at the upper outside corners of the mica openings, a foliated scroll ornament at the lower outside corners of such openings, and a vertically-elongated ornament separating the two mica openings, composed of a patera in the middle part, a loop-and-egg ornament at the ends, and a conventionalized rib-in-35 closed shell intermediately of the patera and 40 loop-and-egg ornaments.

6. In a design for a stove, the design for a front fire-place door herein shown and described, consisting of four vertically-elongated mica openings arranged in a horizontal row 45 in the upper portion of the dcor, which has a plane general surface with rounded upper and vertical edges, six vertically-elongated draft-openings arranged in a horizontal row in the lower portion of the door which has a convexed general surface with rounded vertical edges, and a horizontally-elongated pock-opening intermediately of the two horizontal rows of openings.

In testimony whereof we have hereunto set 55 our hands this 24th day of September, 1890.

H. CLAY BASCOM.
FRANCIS RITCHIE.
